UNITED STATES PATENT OFFICE.

MAX K. GOLDEN, OF DETROIT, MICHIGAN, ASSIGNOR TO DAVID SCHUFF, OF DETROIT, MICHIGAN.

COMBINED LAMP BRACKET AND SPOOL HOLDER.

Application filed January 7, 1924. Serial No. 684,901.

To all whom it may concern:

Be it known that I, MAX K. GOLDEN, a citizen of the United States, residing at Detroit, county of Wayne, State of Michigan, have invented a certain new and useful Improvement in Combined Lamp Brackets and Spool Holders, and declare the following to be a full, clear, and exact description of the same, such as will enable others skilled in the art to which it pertains to make and use the same, reference being had to the accompanying drawings, which form a part of this specification.

My invention relates to a combined spool holder and adjustable lighting bracket for sewing machines or the like.

The object of this invention is to provide a spool holder and light supporting bracket for work tables,—preferably sewing machines for factory or other installations,—the object being to provide a convenient device adapted to be readily regulated by the operator whereby the light may be adjusted directly over the work,—the construction being such that the lamp fixture and spool supporting bracket will not be in the way of the fabric or other material used that the operator may be free to feed or deliver it to the machine without interference.

A further object of the invention is to provide for the longitudinal adjustment of the lamp supporting arm and for swinging it upon its pivot.

A further object of the invention is to provide for supporting a plurality of spools of thread upon the lamp bracket and above the work resting upon the table top.

With the foregoing and other objects in view which will appear as the description proceeds the invention further resides in the combination and arrangement of parts and in the details of construction hereinafter described and claimed it being understood that changes may be made in the precise embodiment of the invention herein disclosed without departing from the spirit of the same.

In the drawings accompanying this specification:

Figure 1 is a plan view of the device showing a pair of spools supported on a platform adjustably attached to the upright portion of the bracket.

Figure 2 is a side elevation of the device

with parts broken away and in section to more clearly disclose the telescopic connection between the lamp arm and the supporting bracket.

Figure 3 is an end elevation of the device attached to a fragmentary portion of a work table or sewing machine top.

Referring now to the letters of reference placed upon the drawings:

A, denotes a fragment of a work table or sewing machine top, to the underside of which is screwed a boss-plate B, preferably tapped to receive the threaded end of a tubular arm D. Sleeved within the bracket arm that it may telescope therewith is a tubular extension E,—to the end of which is secured a lighting fixture F, fitted with a suitable reflector G.

H, indicates a lamp cord housed within the tubular bracket and its extension to connect the lighting fixture with a source of electrical supply,—not shown.

I, represents an adjustable platform having a hub portion I^a sleeved upon the upright portion of the bracket D.

K, indicates a set screw extending through the hub to engage the bracket,—by adjusting which the platform may be secured at any desired altitude upon the bracket.

L, L, denote spools of thread supported upon the platform,—the end of each spool or core extending into sockets I^b, formed in the platform to receive the same.

M designates a thread-guide or standard provided with loops M^a, M^b, through which the thread is adapted to pass to the sewing machine needle.

Having now indicated the several parts by reference letters the construction and operation of the device will be readily understood.

The bracket D, may be swung in either direction in its supporting boss so as to bring the lamp fixture directly above the work,—the telescoping portions of the arm and bracket providing a longitudinal as well as oscillatory adjustment of the arm to direct the light as may be required.

While preferring to depend upon a frictional cooperation between the telescoping parts to hold them in their adjusted relation a set screw or other device may be employed if desired to secure the lamp arm when adjusted.

The platform I, may also be adjusted ver-

tically or axially as required and when properly adjusted the device may be secured to the standard by means of the set screw K.

Having thus described my invention what

5 I claim is:

- In a device of the character described; a vertical tubular bracket having a lateral angularly directed extension adapted to receive a telescoping tubular arm; a boss plate 10 adapted to be secured to a table or other support to receive the end of the bracket axially adjustable therein; an adjustable platform supported upon the bracket having means to receive and support a spool of 15 thread; a standard provided with loops to

receive and guide the thread delivered from the spool; a telescoping tubular arm sleeved within the lateral extension of the bracket fitted at its outer end with a lamp fixture including a reflector, said telescoping tubular arm being longitudinally and axially adjustable in the bracket, whereby it may direct the rays from the lamp fixture upon the thread as it may be sewn.

In testimony whereof, I sign this specification in the presence of two witnesses.

MAX K. GOLDEN.

Witnesses:

L. E. THOMAS,
R. V. COLVIN.
